(57) **CLAIM**

The ornamental design for a weighing scale, as shown and described.

DESCRIPTION

FIG. 1 is a front perspective view of a weighing scale according to the present invention;

FIG. 2 is a rear perspective view thereof;

FIG. 3 is a front elevation view thereof;

FIG. 4 is a rear elevation view thereof;

FIG. 5 is a left side view thereof, the right side view being mirror image thereof;

FIG. 6 is a top plan view thereof;

FIG. 7 is a bottom plan view thereof; and,

FIG. 8 is an enlarged view of an area circumscribed in FIG. 5.

The broken lines in FIGS. 5 and 8 depict boundary of an enlargement of a weighing scale that form no part of the claimed design. The even-space broken lines in FIGS. 2 and 4 depict the portions that form no part of the claimed design.
